EDWARD ANDREWS, OF POTTSVILLE, PENNSYLVANIA.

Letters Patent No. 83,125, dated October 20, 1868; antedated October 9, 1868.

IMPROVEMENT IN BOILER SAFETY-VALVES.

The Schedule referred to in these Letters Patent and making part of the same.

To all whom it may concern:

Be it known that I, EDWARD ANDREWS, of the borough of Pottsville, in the county of Schuylkill, in the State of Pennsylvania, have invented a new and improved Mode of Allowing the Surplus Pressure to Escape from Steam-Boilers; and I do hereby declare that the following is a full, clear, and exact description thereof, reference being had to the accompanying drawings, and to the letters of reference marked thereon.

The nature of my invention consists in providing steam-boilers with a safety-valve that will allow all the surplus pressure to escape under all circumstances.

Figure 1 is an exterior view complete, showing the operation of the weights I and G.

Figure 2 is a view of the arrangement of the piston K, valves W and E, and operation of the yoke D.

Figure 3 is an interior view, showing the operation of the valve J, lever H, and piston K; also, the openings for the valves W and E in the column A and the box B.

To enable others skilled in the art to make and use my invention, I will proceed to describe its construction and operation.

I construct the column A, figs. 1 and 3, having the connection to the valve-box B, containing the pressure-valve J and lever H, and being provided with a cylinder at N, having the piston K to operate in it. Also the valve W, opening inward, as shown at fig. 3, by the opening in the box B.

The valve-box B, enclosing the pressure-valve J and lever H, steam-tight, as shown.

The upper part of the column A being constructed with two valve-seats opposite each other, one opening inward and the other outward, thus presenting an equal surface for the steam to operate upon, and fitted with the double valve E. The pressure being equal on the valve to open or close, it forms a balance-valve.

The end of lever H, fig. 3, operating on piston K, and it being connected to the yoke D, which is also connected to the angle-lever C, having the weight G upon it, allows the pressure to be regulated on the valve J.

The balanced valve E is connected to the lever F, to allow it to be regulated by the weight I, if found

necessary, on account of the larger surface of the valve E being exposed to the pressure when open, and also to close it when released by the yoke D.

The valve W, in the box B, fig. 1, being provided with the stem, slipping through an aperture in the cross-piece of the yoke D, having the set-nuts to regulate it, as shown at fig. 2, the set-nuts 1 1 being adjustable on the stem of the valve W, to control the motion of the piston K, and relieve the pressure in the box B.

The operation is as follows: The column A being secured to the boiler by suitable means, and the steam having free access in the column, acts directly on the valves J and E, and when the pressure on J overcomes the weight on the lever C, the valve J opens, and allows the steam to escape into the box B, and operating on the surface of the piston K, overcomes the resistance of the weights G and I, thereby opening the double valve E by the projecting piece, as shown at M, fig. 2 coming against it, thereby allowing the surplus pressure to escape. The valve W, which has been opened by the same movement, it being regulated by the set-nuts 1 1, allows the steam to escape from the box B, relieves the piston K, and allows the weight G to close the valve J, and at the same time releases the valve E, which is closed by the weight, I, operating on the lever F; the valve W being closed by the same movement when the pressure gets below that required.

It will be observed that the motion of the piston is controlled by the set-nuts, and that the valve W being moved further than the valve J, by the number of fulcrums in the lever H, allows the pressure to escape faster than admitted by the valve J.

Having thus fully described my invention,

What I desire to secure by Letters Patent, is—

1. The arrangement and combination of the balanced valve E with the valve J, lever H, piston K, and yoke D.

2. The arrangement of the box B, enclosing the valves J and W, and lever H.

EDWARD ANDREWS.
